[57] **CLAIM**

The ornamental design for a display rack for eyeglasses and related accessories, as shown and described.

DESCRIPTION

FIG. 1 is a perspective view of a display rack for eyeglasses and related accessories showing my new design, the opposite side being the same in appearance; FIG. 2 is a top plan view thereof;

FIG. 3 is a fragmentary cross-sectional view taken along line 3—3 of FIG. 2;

FIG. 4 is a bottom plan view; and

FIG. 5 is an enlarged fragmentary view showing the upper portion of the display rack in greater detail.

FIG. 1.

FIG. 2.FIG. 3.FIG. 4.

FIG. 5.
